UNITED STATES PATENT OFFICE

129,415

DESIGN FOR A CASING FOR AN ADDING MACHINE

Willis A. Kropp, River Forest, Ill., assignor to Victor Adding Machine Company, Chicago, Ill.,
a corporation of Illinois

Application December 23, 1940, Serial No. 97,571

Term of patent 14 years

To all whom it may concern:

Be it known that I, Willis A. Kropp, a citizen of the United States, residing at River Forest, in the county of Cook and State of Illinois, have invented a new, original, and ornamental Design for a Casing for an Adding Machine, of which the following is a specification, reference being had to the accompanying drawing, forming a part thereof.

I claim:

The ornamental design for a casing for an adding machine, as shown.

WILLIS A. KROPP.
